UNITED STATES PATENT OFFICE.

ARTHUR PRIMROSE YOUNG, OF KENILWORTH, ENGLAND, ASSIGNOR TO GENERAL ELECTRIC COMPANY, A CORPORATION OF NEW YORK.

ELECTRICAL CONTACT MAKING AND BREAKING DEVICE.

Application filed March 10, 1919. Serial No. 281,886.

To all whom it may concern:

Be it known that I, ARTHUR PRIMROSE YOUNG, a subject of the King of Great Britain, residing at Kenilworth, county of 5 Warwickshire, England, have invented certain new and useful Improvements in Electrical Contact Making and Breaking Devices, of which the following is a specification.

- 10 The present invention relates to apparatus for making and breaking electric circuits and more particularly to apparatus for use in a circuit which has to be made and broken a large number of times in quick succession.
- 15 Contact breakers as used in such circuits usually consist of a pivoted lever and a cam, one end of the lever being held in contact with the cam surface by means of a spring, while the other end carries a contact adapted 20 to cooperate with a fixed contact to make and break the circuit when the cam is rotated. Such contact breakers are well known and operate satisfactorily up to a certain critical speed which depends on the spring 25 strength, the moment of inertia and the acceleration of the moving parts. Beyond this critical speed they do not work satisfactorily owing to the fact that the lever will not remain in constant contact with the cam.
- 30 In still another form of contact breaker the cooperating contacts are mounted on two pivoted levers arranged so they engage opposite sides of an actuating cam. Each lever is engaged by a spring so that they are biased 35 to the position in which the contacts are closed, the cam being arranged to simultaneously move the lever in opposite directions to separate the contacts.

This latter form of contact making and 40 breaking device has the advantage that the critical speed at which it will operate satisfactorily is raised to such an extent that it will operate at speeds substantially greater than that obtained by contact breakers such 45 as above described. As the critical speed for given conditions is dependent on the acceleration of the moving parts, it will be obvious that if this movement is reduced the critical speed can be raised. The amount of 50 this movement is seldom less than about twelve thousandths of an inch, so that this is the maximum space separating the fixed and moving contacts during operation, and if both the contacts are simultaneously 55 moved by the cam in opposite directions, the

movement of each contact is only half what would be required were either stationary.

The object of my invention is to provide an improved contact making and breaking device of the latter form, which is simple 60 and compact in construction, and which operates at a substantially higher critical speed than heretofore attained in such devices. In my invention the two levers are preferably U-shaped in form and are pivotally mounted intermediate their ends. 65

Other features of novelty which characterize my invention will appear in the course of the following description and will be definitely pointed out in the appended claims. 70

The invention will be best understood by referring to the accompanying drawings, in which Fig. 1 is an end elevation and Fig. 2 a side elevation, partly in section, of my contact making and breaking device applied to 75 a magneto electric machine.

In the drawings, the cooperating contents 1 and 2 are shown mounted on the adjacent limbs 3 and 4 of two substantially U-shaped levers arranged side by side and preferably 80 pivotally mounted at the bend on the pivots 5 and 6. Leaf springs 7 and 8 are connected to the inner adjacent limbs of the U-shaped levers in such a manner that the levers are normally pressed toward each other to close 85 the contacts. The outer limbs 3' and 4' of the U-shaped levers are arranged so that they engage opposite sides of the four point cam 9 which is rigidly secured to the shaft 10 of the magneto electric machine. For the 90 sake of compactness these outer limbs 3' and 4' are preferably displaced from the plane 95 of the inner adjacent limbs and in the drawings are shown as set in such a plane that the cam is located immediately behind the contact-carrying limbs, and are provided with fibre heels 11 and 12 at the points where they engage the cam. Buffer springs 13 and 14 are arranged to engage the outer 100 limbs 3' and 4' respectively and assist the leaf springs 7 and 8 in holding the levers in contact with the cam so that as the cam rotates they follow the cam surface, the motion being transmitted to the contact-carrying limbs. 105

The lever 3—3' is mounted on a block 15 which is insulated from the base as shown in Fig. 2 and the contact 1 may be electrically connected to the winding of the machine through the leaf spring 7. The other 110

lever 4—4' is mounted on a block 16 directly attached to the base and is therefore connected to ground through the frame of the machine.

- 5 Means such as an adjusting screw 17 in a lug 18 projecting from the base is provided as a stop to be engaged by a projection 19 on the outer end of limb 3' of lever 3—3' and this projection 19 being held 10 in contact with the screw 17 by the springs 7 and 13 insures that the point of engagement of the contacts 1 and 2 will remain fixed in space.

It is desirable that the pressure exerted 15 by the springs 7 and 13 be slightly greater than that exerted by the springs 8 and 14 so as to insure that the projection 19 will be held in engagement with the adjusting screw 17.

20 Having thus illustrated and described what I now consider the best embodiment of my invention, it is obvious that the construction and arrangement of parts may be modified without departing from the 25 spirit of my invention, the scope of which is set forth in the appended claims.

What I claim as new and desire to secure by Letters Patent of the United States, is,—

30 1. A contact making and breaking device comprising a pair of pivoted levers, co-operating contacts mounted one on each lever, said levers being normally spring pressed to contact closing position, a stop 35 for one of said levers whereby the point of engagement of said contacts is fixed, and an actuating cam engaging said levers and adapted to simultaneously move them in opposite directions to separate said contacts.

40 2. A contact making and breaking device comprising a pair of substantially U-shaped levers arranged side by side, cooperating contacts mounted on corresponding limbs of said levers, each pivotally mounted intermediate 45 its ends, said levers being normally spring pressed to contact closing position, and an actuating cam arranged to engage the other corresponding limbs of said levers and adapted to simultaneously move said 50 levers in opposite directions to separate said contacts.

3. A contact making and breaking device comprising a pair of substantially U-shaped levers pivotally mounted side by side, co- 55 operating contacts mounted on corresponding limbs of said levers, said levers being normally spring pressed to contact closing

position, a stop for one of said levers whereby the point of engagement of said contacts is fixed, and an actuating cam arranged to 60 engage the other corresponding limbs of said levers and adapted to simultaneously move said levers in opposite directions to separate said contacts.

4. A contact making and breaking device 65 comprising a pair of substantially U-shaped levers pivotally mounted side by side, co-operating contacts mounted on the adjacent limbs of said U-shaped levers, the outer limbs of said levers being displaced from the plane of the two adjacent contact-carrying limbs, said levers being normally spring pressed to contact closing position, and an actuating cam engaging the outer limbs of 70 said levers and adapted to simultaneously move said levers in opposite directions to separate said contacts.

5. A contact making and breaking device 75 comprising a pair of substantially U-shaped levers pivotally mounted side by side, co-operating contacts mounted on the adjacent limbs of said U-shaped levers, the outer limbs of said levers being displaced from the plane of the two adjacent contact-carrying limbs, said levers being normally spring 80 pressed to contact closing position, a stop for one of said levers whereby the point of engagement of said contacts is fixed, and an actuating cam engaging the outer limbs of said levers and adapted to simultaneously move said levers in opposite directions to 85 separate said contacts.

6. A contact making and breaking device 90 comprising a pair of substantially U-shaped levers mounted side by side and each pivoted at its bend, cooperating contacts mounted on the adjacent limbs of said U-shaped levers, the outer limbs of said levers being displaced from the plane of the two adjacent contact-carrying limbs, said levers being 95 normally spring pressed to contact-closing position, a stop for one of said levers whereby the point of engagement of said contacts is fixed, and an actuating cam engaging the outer limbs of said levers and adapted to simultaneously move said levers in opposite directions to 100 separate said contacts.

In witness whereof, I have hereunto set my hand this fourteenth day of February, 1919.

ARTHUR PRIMROSE YOUNG.
